GRAY L. MORRISS, OF CHICAGO, ILLINOIS, ASSIGNOR TO RELIANCE DRYING ROOM CO.,
OF CHICAGO, ILLINOIS, A CORPORATION OF ILLINOIS.

DRYING-ROOM.

1,203,234.

Specification of Letters Patent.

Patented Oct. 31, 1916.

Application filed December 13, 1915. Serial No. 66,525.

To all whom it may concern:

Be it known that I, GRAY L. MORRISS, a citizen of the United States, residing at Chicago, in the county of Cook and State of Illinois, have invented certain new and useful Improvements in Drying-Rooms, of which the following is a specification:

This invention relates particularly to a drying room intended for baking enamel on metallic surfaces, as, for instance, automobile bodies or the like.

The objects of the invention are to so arrange the heating and air circulating devices as to maintain a substantially uniform degree of heat and dryness throughout the drying chamber; and to provide for the ready introduction of automobile bodies or the like into the drying chamber by the provision of a turn-table floor so arranged as to be exposed one-half within the drying chamber, and the other half outside of the chamber, to the end that the stacking up of one charge of enamel ware or the like may proceed concurrently within the drying or baking of another charge, thereby expediting the drying operation and conserving the heat within the drying room to the greatest possible extent.

The invention, furthermore, relates to the closure for the drying room which is mounted upon and rotated with the turn table in such a manner as to open and close the drying room by the act of rotating the turn-table, so that the charge of enamel ware may be introduced into the drying or baking room simultaneously with the removal of the preceding charge and a closure effected so quickly as to prevent the escape of heat from the drying room.

In the drawings: Figure 1 is a front elevation of the drying room showing the rotating door or closing wall removed to expose the interior; Fig. 2 is a sectional plan view of the same, showing the rotating door in place; Fig. 3 is a top or plan view showing the arrangement of the circulating and ventilating pipes; and Fig. 4 is a detail of the same in side elevation.

The drying or baking room 5, as shown, is of semi-polygonal shape, closely proximating the outline of the turn-table 6 which forms the floor of the drying chamber. The drying chamber is formed by a vertical wall 7 of the shape mentioned, which wall is enclosed with double exterior walls 8 extend-

ing in angular relation to one another, and each terminating in a short inwardly extending double wall 9 which terminates in vertical alinement with the periphery of the turn-table, giving to the exterior of the structure the shape, in plan, of a square having one of its corners cut away or truncated. The inner terminal edges of the walls 9 are in alinement with the greatest diameter of the turn-table, so that half of the latter projects exteriorly of the drying or baking chamber 5, from which the projecting portion is separated by a double-walled rotating door 10 built upon and vertically extending from the turn-table and adapted to rotate therewith. The ends 11 of the rotating door are laterally spread or extended to furnish bearing surfaces contacting with or in very close relation to the inner edges of the walls 9, so that when the turn-table is moved to the position shown in Fig. 2, the rotating door will serve to close the drying or baking chamber, thereby preventing the escape of heat units therefrom, and also preventing the ingress of moisture or dust. The exterior walls are in spaced relation with respect to the polygonal wall of the drying or baking chamber, and this affords a central heating chamber 12 and supplemental heating chambers 13 in communication with the central heating chambers, the arrangement being one which affords, in effect, a continuous heating chamber around the entire inner surface of the drying or baking chamber. The heating chambers have located therein heating coils 14 or the like, adapted to heat the air delivered to the drying or baking chamber.

The polygonal baking chamber wall 7, as shown, is open at the top and bottom to permit the circulation of air from the heating chamber over and under said wall, but in order to induce and maintain a more rapid and uniform circulation of heated air, a system of circulating pipes is employed, which will now be described.

Vertical air eduction pipes 15 and 16 lead from the central and auxiliary heating chambers respectively, which vertical eduction pipes are inturned at their lower ends and project through the exterior walls near the floor level, which pipes serve to create a circulation or suction of air from the drying or baking chamber underneath the lower edge of the polygonal wall. These eduction

pipes 14 and 15 extend to a point above the level of the ceiling or top 17 of the structure, at which point their ends 18 and 19 are in-turned and converged together in a drum 20, which communicates with a fan or blower 21 having a discharge pipe 22, which is down-turned through the ceiling near the center of the drying or baking room and serves to discharge the educted air back into the drying or baking room, and to maintain the circulation therethrough, and to induce additional circulation of heated air directly over the upper edge of the inner polygonal wall of the drying or baking chamber, thereby serving to induce currents of air directly from the coils, and into the top of the drying or baking room.

In order to provide for the eduction of foul or saturated air from the drying or baking room, a plurality of ventilating pipes 23 and 24 are provided which extend upwardly through the ceiling of the structure, and communicate respectively with the drying room and the heating chamber, and these pipes 23 and 24, at their upper ends, communicate with the angles of a triangular header pipe 25, which at points intermediate its angles communicates with inwardly extending leads of pipe 26 which converge together and merge into a single ventilating flue 27 adapted to educt the foul or saturated air to a suitable point of discharge. Suitable provision may also be made for the introduction of fresh air, if desired, but, of course, the opening and closing of the rotating door, due to the movements of the turn table, will admit a considerable volume of fresh air, and additional air will ordinarily not be required except in special circumstances.

In use, the automobile bodies, or other enamel ware or articles, desired to be dried, will be stacked up on the exposed portion of the turn-table, and after the stack is complete, the turn-table will be rotated to turn the previously exposed section back into the drying or baking chamber, after which the fan or blower can be started and the drying proceeded with. During the interval required for drying, a second charge of enamel ware or the like can be stacked up, so that, by the time the first charge has been dried or baked, a succeeding charge can be immediately turned back into position. This not only greatly expedites the operations involved, but also tends to conserve the heat units and obviates the necessity for the workmen entering into the highly heated baking or drying chamber, which is not only unpleasant but is also prejudicial to health in view of the presence in greater or less quantity of the fumes from the varnish or enamel. The arrangement is one which permits the articles to be stacked up carefully, and under most favorable conditions, is

economical of floor space and more satisfactory from every standpoint than would be the case if the turn-table were not employed. The employment of a rotating door or closing wall mounted upon the turn-table itself insures the immediate closing of the door as the articles are turned back in place, thereby conserving the heat units and preventing the stirring up of dust and simplifying the operations involved to the utmost.

I claim:

1. In a drying room, the combination of exterior walls, an interior wall in spaced relation thereto affording an intermediate heating chamber, an interior drying chamber in communication with the heating chamber, heating means located in the heating chamber, a turn-table floor for the drying chamber extending partially to the exterior thereof, and a door extending transversely of the turn-table for closing the drying chamber, substantially as described.

2. In a drying room, the combination of exterior walls, an interior wall in spaced relation thereto affording an intermediate heating chamber, an interior drying chamber in communication with the heating chamber, heating means located in the heating chamber, a turn-table floor for the drying chamber extending partially to the exterior thereof, and a door mounted upon and rotatable with the turn-table and extending transversely thereof and in position to close the drying chamber when turned in position to extend to the walls thereof, substantially as described.

3. In a drying room, the combination of exterior walls, an interior wall in spaced relation thereto affording an intermediate heating chamber, an interior drying chamber in communication with the chamber, heating means located in the heating chamber, a turn-table floor for the drying chamber extending partially to the exterior thereof, a door extending transversely of the turn-table for closing the drying chamber, and a blower for maintaining currents of air through the drying chamber, substantially as described.

4. In a drying room, the combination of exterior walls, an interior wall in spaced relation thereto affording an intermediate heating chamber, an interior drying chamber in communication with the heating chamber, heating means located in the heating chamber, a turn-table floor for the drying chamber extending partially to the exterior thereof, a door mounted upon and rotatable with the turn-table and extending transversely thereof and in position to close the drying chamber when turned in position to extend to the walls thereof, and a blower for maintaining currents of air through the drying chamber, substantially as described.

5. In a drying room, the combination of exterior walls, an interior wall in spaced relation thereto affording an intermediate heating chamber, an interior drying chamber in communication with the heating chamber, heating means located in the heating chamber, a turn-table floor for the drying chamber extending partially to the exterior thereof, a door extending transversely of the turn-table for closing the drying chamber, a pipe communicating with the drying chamber near the bottom thereof and leading upwardly therefrom, a blower connecting with said pipe, and a pipe leading 10 from the blower to the top of the drying chamber for recirculating the air therethrough, substantially as described.

6. In a drying room, the combination of exterior walls, an interior wall in spaced relation thereto affording an intermediate heating chamber, an interior drying chamber in communication with the heating chamber, heating means located in the heating chamber, a turn-table floor for the drying chamber extending partially to the exterior thereof, a door mounted upon and rotatable with the turn-table and extending transversely thereof and in position to close the drying chamber when turned in position 20 to extend to the walls thereof, a pipe communicating with the drying chamber near the bottom thereof and leading upwardly therefrom, a blower connecting with said pipe, and a pipe leading from the blower 25 to the top of the drying chamber for recirculating the air therethrough, substantially as described.

7. In a drying room, the combination of exterior walls, an interior wall in spaced relation thereto affording an intermediate heating chamber, an interior drying chamber in communication with the heating chamber, heating means located in the heating chamber, a turn-table floor for the drying chamber extending partially to the exterior thereof, a door extending transversely of the turn-table for closing the drying chamber, a pipe communicating with the drying chamber near the bottom thereof 40 and leading upwardly therefrom, a blower connecting with said pipe, a pipe leading from the blower to the top of the drying chamber for recirculating the air therethrough, and a ventilating flue leading from the drying chamber for educting foul or 45 saturated air therefrom, substantially as described.

8. In a drying room, the combination of exterior walls, an interior wall in spaced relation thereto affording an intermediate heating chamber, an interior drying chamber in combination with the heating chamber, heating means located in the heating chamber, a turn-table floor for the drying chamber extending partially to the exterior 50

thereof, a door mounted upon and rotatable with the turn-table and extending transversely thereof and in position to close the drying chamber when turned in position to extend to the walls thereof, a pipe communicating with the drying chamber near the bottom thereof and leading upwardly therefrom, a blower connecting with said pipe, a pipe leading from the blower to the top of the drying chamber for recirculating the air therethrough, and a ventilating flue leading from the drying chamber for educting foul or saturated air therefrom, substantially as described. 55

9. In a drying room, the combination of exterior walls, an interior wall inclosing a drying chamber and in spaced relation with the outer walls to afford a heating chamber, said interior wall being open at the top and bottom to afford communication between the said chambers, heating means in the heating chamber, a turntable floor for the drying chamber partially extending exteriorly thereof, and a door extending transversely of the turn-table for closing the drying 60 chamber, substantially as described.

10. In a drying room, the combination of exterior walls, an interior wall inclosing a drying chamber and in spaced relation with the outer walls to afford a heating chamber, said interior wall being open at the top and bottom to afford communication between the said chambers, heating means in the heating chamber, a turn-table floor for the drying chamber partially extending exteriorly thereof, a door extending transversely of the turn-table for closing the drying chamber, and a door mounted upon and rotatable with the turn-table and extending transversely thereof and adapted to 65 close the drying chamber when turned to position to extend between the walls thereof, substantially as described. 70

11. In a drying room, the combination of interior and exterior walls in spaced relation to afford a heating chamber between them and a drying chamber inside of the inner wall, said inner wall being open at the top and bottom to afford communication between the two chambers, heating means in the heating chamber, a pipe leading from the bottom of the heating chamber, a blower in communication with said pipe, and a pipe leading from the blower into the top of the drying chamber for 75 maintaining and inducing currents of heated air therethrough, substantially as described. 80

12. In a drying room, the combination of interior and exterior walls in spaced relation to afford a heating chamber between them and a drying chamber inside of the inner wall, said inner wall being open at the top and bottom to afford communication between the two chambers, heating means in 85

the heating chamber, a plurality of pipes leading from different points at the bottom of the heating chamber and extending upwardly to a point and uniting together and connecting with a blower, and a pipe leading from the blower communicating with the drying chamber at the top thereof for

maintaining and inducing currents of heated air therethrough, substantially as described.
